UNITED STATES PATENT OFFICE.

WILLIAM B. DENNIS, OF BLACKBUTTE, OREGON.

METHOD OF PRODUCING GAS.

No. 863,462.

Specification of Letters Patent.

Patented July 14, 1908.

Application filed March 1, 1906. Serial No. 303,692.

To all whom it may concern:

Be it known that I, WILLIAM B. DENNIS, a citizen of the United States, residing at Blackbutte, in the county of Lane, Oregon, 5 have invented certain new and useful Improvements in Methods of Producing Gas; and I do hereby declare the following to be a full, clear, and exact description of the invention, such as will enable others skilled in 10 the art to which it appertains to make and use the same.

My invention relates to improvements in methods of making producer gas, and it is intended more especially for making producer gas from any kind of fuel for use in furnaces, but it is not confined to this use, as it may be used for all metallurgical and heating purposes, and also for power and illuminating purposes, when properly scrubbed enriched 20 and cooled as may be required.

The distinctive feature of my method consists in oxidizing the fuel mass gradually, or by degrees, in progressive zones of combustion, by the admitting to each zone a volume 25 of air measured in proportion to the temperature of the fuel in such zones and of causing the evolved gases and vapors of each zone to pass into and through the next succeeding zone in the line of progression of the combustion process; the travel of the evolved gases or products of combustion being always from a zone of lesser to one of more advanced combustion, or from a cooler to a hotter zone. Beginning with the zone of incipient combustion 30 the evolved gases moving from zone to zone pass through the entire fuel mass, and are discharged from the hottest zone of final combustion at a point below the last air inlet of the combustion series, and the evolved 35 gases, or combustion products, are caused, after being discharged from the last or final oxidizing zone at a point below the last air inlet of the combustion series, to pass into and through a reducing or enriching zone or 40 receptacle containing highly heated or incandescent carbon, and preferably to pass through said carbon, and into which zone no oxygen or air is admitted other than that already contained in the fuel gases admitted 45 thereto. In combination with the foregoing, I also preferably employ what is commonly known as a down draft, preferably produced by mechanical suction. This method of oxidizing fuel and generating heat and gas 50 therefrom may be conveniently described as 55 "gradual combustion" and in practical

operation it consists of dividing the fuel mass and the receptacle containing it, into a series of units or zones and of supplying each unit with the minimum amount of oxygen, 60 or air, which can chemically combine with the fuel elements at the temperature of such unit, thereby procuring the decomposition of the fuel gradually, beginning with the initial unit of nascent combustion at one end 65 of the fuel mass or receptacle and progressing from unit to unit, or zone to zone, until complete decomposition is accomplished at the last or final zone of combustion. By this method perfect chemical union of the evolved 70 fuel elements with the air at or near the theoretical chemical minimum is secured, resulting in the complete gasification of the fuel and the production of a uniform gas free of tarry impurities. The uniform constituency 75 of the gas is further assured by causing it to pass through a reducing zone as above described.

The process is simple, economic and harmonious, and is especially valuable in gasifying 80 large masses of fuel.

In making gas, oftentimes the volume of air required to support combustion of the entire fuel mass is admitted at one or more points, usually an excess volume, and without regard to the temperature or chemical requirements of the fuel at the point of admission. Under these conditions perfect mixture and the complete and uniform gasification of the entire fuel mass is impossible. 85 The fuel zone immediately adjacent to the admission point burns rapidly with a great excess of air while areas of the fire farther removed are not supplied with sufficient oxygen to support perfect combustion. 90 Under these conditions uniform elementary change throughout the combustion area is impossible. A confusion of chemical actions and reactions is set up, due to imperfect mixture and greatly varying temperatures 95 within narrow limits, resulting in loss of fuel values due to incomplete decomposition of some portions of it and in the production of an un-uniform gas, and the highly objectionable semi-distillation products. 100

By my method of gradual combustion the air is supplied at frequent intervals, to each unit or zone in amount proportional to the capacity of the fuel elements in such zone to chemically combine therewith, the measure 110 of which capacity is the temperature of the fuel in such unit or zone.

In the zone of incipient oxidation, where the temperature is comparatively low only water vapor (H_2O) is liberated, and only sufficient air is supplied to produce this result. In the next zone of the series the temperature being somewhat higher than the preceding one, the lighter hydrocarbons are released, and sufficient additional air only is supplied to support this degree of combustion. In like manner from zone to zone the process of combustion is advanced gradually, or by degrees, and sufficient additional air is supplied to each zone to support the proportional duty of that zone to the whole process, until complete oxidation has been accomplished finally in the last combustion zone of the series, and the gaseous products are delivered into the reducing chamber, as previously described, where the well known chemical reaction takes place resulting in reduction of the carbon dioxid (CO_2) and water (H_2O) into carbonic oxid (CO), and hydrogen (H). These gases, as they pass to the holder, or to the place of consumption, are of course mixed with the nitrogen of the air admitted into the producer.

It is evident that by this method, which is exceedingly simple and capable of general application, perfect mixture of air with the evolved gases is secured; that the supply of air may easily be regulated in proportion to the chemical requirements, and that the entire fuel body is uniformly oxidized without any of the objectional semi-distillation products, and without loss of any portion of the calorific value of the fuel.

The above method is applicable to generating heat and gas from any kind of fuel and may be carried out in various forms of apparatus, one of which is shown in the accompanying drawings, in which—

Figure 1 is a vertical section of a gas producer for carrying out my improved method as applied to a roasting furnace; Fig. 2 is a horizontal cross section of the same; Fig. 3 shows the manner of generating and supplying gas to an engine, showing the gas producer and scrubber in cross section, a gasometer, and an engine, and Fig. 4 is a vertical cross section of a modified form of my gas producer.

In the drawings I have shown in Figs. 1 and 2 one suitable form of a gas producing apparatus, of which the generator element is a vertical shaft of suitable form and material, although of course a horizontal generator could be employed. A series of air inlets, controlled by valves, and placed at suitable intervals, extends from top to bottom of the fuel containing receptacle, each inlet corresponding to a zone of oxidation as described. Air inlets are placed also in the reducing zone and gas passage underneath the reducing zone, but these inlets are intended for emergency purposes only. The

fuel rests upon grate bars or arches constructed of suitable fire resisting material. The grate is so arranged that live coals will drop through it into the reducing zone. This zone is placed underneath the fuel grate in a convenient position to receive the coal droppings from the reducing zone as described and is provided with a grate floor constructed of suitable fire resisting material and upon which are retained the live coals which drop through the upper or fuel grate until such coals have been reduced to ashes. In a convenient position underneath or beyond the reducing chamber is the gas passage and ash pit. The grate floor of the reducing chamber may be omitted, if desired, and the gas passage used as a reducing chamber. The operation of this gas producer is as follows:—The fuel is fed through a hopper at the top, and the fire being started, the fuel receptacle is kept well filled. The valve controlling the top air inlet of the series is opened sufficiently to admit the requisite volume of air, the measure of which is the temperature of the corresponding fuel zone. In like manner the remaining air inlets of the series, always under separate control, are opened sufficiently to admit the requisite volume of air corresponding to the duty of each zone as previously described, always proportional to the temperature of the fuel therein.

The gaseous products of each zone are pulled downward always from a cooler to a hotter zone as described, a suction draft being employed. Finally the gases are discharged into the reducing chamber at a point below the last air inlet of the series, and after passing through the reducing chamber in the presence of highly heated or incandescent carbon are discharged underneath the grate thereof into the gas passage leading to the gas holder, combustion chamber or furnace, as the case may be.

85 represents the fuel receptacle located on the rear of the furnace and provided with a fuel hopper 86 closed by a swinging cover 87, a conveyer 88 being located in proximity thereto. The fuel hopper is provided with a sliding plate or door 116, which separates it from the fuel receptacle proper. Connected to the fuel hopper 86 is a smoke pipe or flue 89, which may be desirable to use in starting the fire, or in case of emergency, when the operation of the suction fan, not shown in Fig. 1, is stopped, and when it is desired to shut off the gas from the furnace by closing the dampers in the gas passage leading thereto. The smoke pipe or flue 89 is provided with a movable valve 90, which in the ordinary operation of the furnace is closed.

91 represents a removable cover in the pipe 89, so that access may be had to the valve 90 for the purpose of luting it in position, when desired.

The form of gas producer best adapted for my purpose is of the suction type, the air being forcibly drawn in through the gas producer and the entire furnace.

5 The fuel chamber 85 is provided with a grate 93, of any suitable construction. Below this fuel chamber is the reducing chamber 80, which is provided with a grate 94 for the purpose of catching and retaining any 10 incandescent coals that may pass through the grate 93.

Sufficient air, without undue excess, is introduced into fuel chamber 85 to completely oxidize its entire fuel contents. This air is 15 admitted in regulated quantities through several air inlets, as described, in gradual steps of progression so that perfect and uniform mixture is secured. The resultant product of CO_2 gas is then drawn off or discharged 20 from generator chamber 85 at a point below or beyond the last air inlet of the combustion series of inlets and is delivered to or sucked through reducing chamber 80 which is a closed chamber into which no additional 25 air is admitted. This chamber being filled, or partially filled, with incandescent carbon, the CO_2 gas is reduced to CO by the well known chemical reaction. The carbon monoxide is now delivered to, or sucked into, gas 30 holder or distributing chamber 97 as described, and is ready for use or further delivery as required to coolers, scrubbers, or to direct fired furnaces. Before final use, it is supplied with the requisite air, preferably 35 heated, and is burned to CO_2 . The quantity of air supplied is always in proportion to the temperature of the fuel or gas at the point, or unit, of mixture in accordance with my method of gradual combustion as described.

40 The fuel chamber 85 is provided with a number of openings, such as 95, for the admission of air. Each opening is provided with a valve 96, so that the amount of air admitted to any part of the gas producer may 45 be exactly regulated in proportion to the temperature of the fuel in the zone corresponding to each air inlet, and the amount of air admitted is so regulated that the lowest temperature is at the top where the fuel is 50 fed in, and the temperature gradually and steadily increasing, beginning with the zone of nascent combustion corresponding to the topmost inlet and extending through a series of zones of progressive combustion, until 55 the gas is discharged into the gas holder, this being a part of my principle of gradual combustion.

97 represents the distributing chamber which is simply a large chamber located in a 60 convenient position to receive the gas after it has passed through the reducing zone 80, and to distribute it to the furnace, or to the place or places where it is to be burned or utilized.

65 Figs. 1 and 2 of the drawings illustrate the

distribution of the gas at several points of a furnace such as is described in my original application No. 294,594, filed January 4, 1906. In the example given in the illustration, the distributing chamber 97 communicates, by means of horizontal passages 98 and 99, Fig. 2, with the gas flues 100 and 101 located immediately in the rear of the series of combustion chambers on either side of the furnace. The distributing chamber and the 70 passage leading therefrom to the furnace are provided at intervals with air inlet openings in accordance with my principle of gradual combustion, previously described. The gas flues 100 and 101 are closed at the top, and 75 communicate directly with a series of combustion chambers, 48 and 49, on either side of the furnace, through openings, such as 106.

30 and 31 represent air chimneys or passages, which are connected to the gas flues 35 100 and 101 by passages 107 closed by valves 108.

Means are provided for cleaning the lower part of the gas producer and distributing chamber and 112 is a removable door through 30 which the ashes may be raked out.

The air inlet openings 109 and 110 below the grate bars 93 and 94 are usually kept closed and in this case the chamber 80 between these sets of grate bars acts as a reducing zone, reducing, by the action of the incandescent coals on said grate bars, any carbonic acid gas, (CO_2) to carbon monoxide, (CO). If it should happen that there is too large an accumulation of coals on and underneath the grate bars 94 the surplus carbon may be easily and quickly burned by opening one or both of the two lowest air inlets, 109 and 110.

In the usual operation of the apparatus 105 described, the air inlets located below the grate 94 do not belong to the series of combustion air inlets previously described, and are not used. These air inlets are intended for use only for emergency purposes, as for 110 example, when a large mass of coals falls through the lowest grate and it is necessary, for the proper working of the apparatus, to burn these coals.

In the form of producer above described 115 the fuel receptacle is an undivided chamber of single unit. The several zones of the combustion series described are not mechanically separated from one another, but are defined, or designated, only by the corresponding air 120 inlets, and in operation these zones merge one into the other constituting a series of merging zones of progressive combustion as described.

Various forms of producers may be used 125 for applying my method of gradual progressive combustion according to the fuel utilized or other specific conditions or requirements.

In Fig. 4 is shown another form of pro- 130

ducer in which the combustion zones are mechanically separated from one another by divisional floors or grate bars of suitable material. The general construction of this is the 5 same as already described, the parts 87, 88, 89, 90, 91, 93, 94, 95, 109, 110, and 112 being of the construction already described. In this 10 form of producer, however, the combustion chamber proper is divided into distinct zones by means of sets of grate bars 114, 115 and 117, each of these zones being provided with an air inlet so that the temperature in such zone may be exactly regulated. In the drawings only four combustion zones and 15 but one air inlet for each zone is shown, but it is evident that any convenient number of combustion zones, and a plurality of such air inlets arranged at any convenient points around the combustion chamber, might be used. The grates 114, 115, and 117 are 20 dumping grates, each of the bars terminating in a cranked portion 118 provided with a pin 119, adapted for operation by any suitable means. The bars of each grate are, of course, 25 connected together, so that they may be simultaneously operated.

Any convenient form of grate bars may be used, and any suitable mechanical device employed for operating them. In the drawings dumping bars are shown, but shaking grates or any other convenient form may be used. When placed in position they should be set a suitable distance apart to permit the easy flow of gases between them. In this 30 form of the producer, the fire is started on the lower grate 93, and after combustion has sufficiently advanced the upper zones are filled or partially filled with fuel and as required the fuel is dumped or shaken from 35 one zone to the next succeeding in the line of advancing combustion, always from a cooler to a hotter zone. After each discharge a fresh supply of fuel is charged into the top zone through hopper 86 and the operation repeated. The fuel is positively divided into different zones, in each of which the temperature may be accurately regulated. The grates 93 and 94 are not dumping grates but of the ordinary construction, 40 as already described in connection with Figs. 1 and 2. 113 represents the gas delivery pipe.

Referring to Fig. 3, which illustrates the method of making, scrubbing, and storing producer gas, and supplying it to an engine, 45 1 represents an explosive engine, of any desired type, which communicates by means of the pipe 2 with the gasometer 3, which is of the usual construction, having a bell 4 and counter-balancing weights 5 connected to 50 said bell 4 by ropes passing over pulleys 6. 7 represents a pipe connecting the fan 8 with said gasometer, and 9 represents a pipe connecting said fan with the upper part of the scrubber 10, which is filled with any desired

purifying material, to the upper part of 65 which is supplied a jet of water through the pipe 11, which is bent, as shown at 12, to provide a water seal. 85 represents the gas producer, and 113 the gas delivery pipe leading from the lower part of the producer into the 70 lower part of the scrubber.

If desired, the air admitted through the air inlets 95 may be heated, but this is not usually necessary.

My method of producing gas is useful not 75 only with the particular furnace shown in Figs. 1 and 2 of the drawings, but also with any kind of a furnace, and for heating, power, and illuminating purposes generally after being enriched, and may be used for producing 80 gas from any kind of fuel.

Having thus described my invention, what I claim as new and desire to secure by Letters Patent of the United States, is:—

1. The process of producing gas, which 85 consists in burning fuel gradually and steadily in a series of progressive steps advancing from incipient to complete oxidation, dividing the fuel body into a series of zones corresponding to the steps in the process of combustion and admitting to each zone a measured volume of air proportional to the temperature in such zone and just sufficient to produce substantially equal increments of heat in each zone over the preceding zone, 90 substantially as described.

2. The process of producing gas, which consists in gasifying fuel gradually and steadily in a series of progressive steps advancing from the incipient stage to complete 100 oxidation, dividing the fuel body into a series of zones corresponding to the progressive steps in the process of gasification, and admitting to each zone a measured quantity of air proportional to the temperature in 105 such zone and just sufficient to produce substantially equal increments of heat in each zone over the preceding zone, the amount of air admitted into all the zones of the series being just sufficient to finally produce complete gasification of the fuel, substantially as 110 described.

3. The process of producing gas, which consists in decomposing fuel gradually and steadily in a series of progressive steps advancing from incipient to complete decomposition, dividing the fuel into a series of zones corresponding to the steps in the process of decomposition, admitting to each zone a measured quantity of air proportional to 115 the capacity of the fuel at its prevailing temperature in such zone, to form an intimate chemical union with the air so admitted, the total quantity of air admitted being substantially just sufficient to produce complete 120 decomposition of the entire fuel mass, and in the progress of the process causing the products of decomposition to flow from each zone 125

through and into the next zone of the series, and always from a cooler to a hotter zone, substantially as described.

4. The process of producing gas, which consists in gasifying fuel gradually in a series of zones starting with incipient combustion in an initial zone and gradually growing hotter in each succeeding zone until complete gasification takes place in the final zone, supplying under control measured quantities of air to such zones just sufficient to cause substantially equal increments of heat in each zone over the preceding zone, the quantity of air thus supplied to each zone being proportional to the temperature of said zone, and the capacity of the fuel therein to form an intimate chemical union therewith, the sum total of the air supplied to all the zones being substantially just sufficient to produce complete gasification, causing the fuel and the products of combustion to move from one zone to the next through the entire series of zones, and always from a cooler to a hotter zone, and finally causing the incandescent fuel and products of combustion to move into a reducing zone sealed against air, and causing the gasified products of combustion to pass through said reducing zone and be discharged therefrom at the hottest point of the operation, substantially as described.

5. The process of producing gas, which consists in dividing a column of fuel into a

series of zones composed of a plurality of combustion zones and one reducing zone at 35 the end of the series, starting incipient combustion in the initial zone, and advancing the process of combustion regularly in each of the succeeding combustion zones supplying under control to each combustion zone a 40 measured quantity of air proportional to the quantity of fuel in said zone and to the capacity of fuel in said zone to form an intimate chemical union with the air thus supplied, sealing the reducing zone of the series 45 against the admission of any extraneous air, causing the fuel and the products of combustion in each zone to move in a continuous stream from one zone to and through the next, starting with the initial zone and 50 always moving to a hotter zone, and finally causing incandescent fuel to continuously move from the last combustion zone of the series into the reducing zone, and causing the gaseous products of combustion to flow 55 in a continuous stream into and through said reducing zones and to be discharged therefrom at the hottest point of the operation, substantially as described.

In testimony whereof, I affix my signature, 60 in presence of two witnesses.

WILLIAM B. DENNIS.
